1**2,916,195****BOX-LIKE CARTONS****Harry Frederick Gatward, East Grinstead, England****Application January 10, 1957, Serial No. 633,430****Claims priority, application Great Britain
September 20, 1956****2 Claims. (Cl. 229—52)**

This invention relates to box-like cartons composed of cardboard or similar sheet material, the chief object of the invention being to evolve an improved carton which can be economically manufactured and which will avoid the necessity for the use of staples or other fastening devices for maintaining the carton in its box-like form.

A carton in accordance with the present invention is produced from a single blank of cardboard or similar sheet material without the aid of staples or other securing devices, the ends of the carton being closed by overlapping flap-like parts, some of which interlock to maintain the carton's box-like form, and others are formed to provide an integral carrying handle.

It will be appreciated that such a carton can, therefore, be distributed to the users in its original flat condition, and in that condition will occupy a minimum of space both during storage and transit, and can be quickly and easily folded into its box-like form when required for use. Furthermore, the carton after use can, if it is to be returned to the distributor, be returned to its original flat condition to facilitate transport.

The carton in accordance with the present invention has been designed primarily for carrying bottled beverages, for example, four bottles, but can be easily designed to carry any number of bottles, within reason or to contain other commodities.

According to a further feature of the invention, the bottom of the carton is so formed that it has good shock-absorbing qualities, thus rendering the carton particularly suitable for carrying fragile articles such as, for example, glass bottles.

Referring to the drawings:

Figure 1 is a plan view of the blank from which one carton in accordance with the invention is constructed;

Figure 2 shows the blank in process of being folded to produce the carton;

Figures 3, 4, 5 and 6 illustrate further stages in the folding operation;

Figure 7 is a perspective view of the folded carton;

Figure 8 is a perspective view illustrating the bottom of the carton;

Figure 9 is a plan view looking down into the interior of the carton;

Figure 10 is a plan view of the blank used in the manufacture of a larger size carton;

Figure 11 is a perspective view illustrating this carton in the final stage of folding;

Figure 12 is a fragmentary perspective view illustrating the carton in its fully folded condition; and

Figures 13 and 14 illustrate constructional details which are applicable to either form of carton.

Referring in the first case to the construction illustrated in Figures 1 to 9, the blank, which is preferably produced from sheet corrugated or other type of cardboard, includes five rectangular portions indicated by reference numeral 10, formed with crease lines 11, these rectangular portions being intended to form the sides of

2

the carton, the endmost rectangular portions overlapping so that one side of the carton is of double thickness.

The rectangular portions 10 carry at their opposite extremities flap-like portions, hereinafter referred to, 5 which are connected with the portions 10 by crease lines 12.

The flap portions which are intended to form the bottom of the carton are indicated by reference numerals 1a-5a, whilst the flap portions which serve to close the 10 carton at its upper end are indicated by reference numerals 1-5.

The flap portions 1a-5a, as is clearly shown in Figure 1, are of substantially right-angle triangle form but are each provided with a curved protuberance 13 which 15 projects from the hypotenuse of the triangle and provides a recess 14. The endmost flap portions 1a and 5a are slotted respectively at 15 and 16, slot 15 being double or approximately double the width of slot 16. The flap portions, which are intended to close the carton at its 20 upper end, include three handle carrying flaps 2, 4 and 5 which are again of right-angle triangle formation and are formed with handle portions 17 which project from the hypotenuse and are each formed with a slot 18 for the entry of the fingers when the carton is being carried. 25 The handle portions 17 are connected with the triangular flaps, 2, 4 and 5 by means of crease lines 19.

The remaining flaps 1 and 3 are of square formation and are each formed with a diagonally positioned slot 20 of a length equal to the width of the handle 30 portions 17.

If reference is now made to Figures 2 to 7, the manner of folding the blank will be clearly seen. The blank is first folded along the crease lines 11 and the flap portions 1a-5a are then folded inwardly to close 35 the bottom of the carton. The slits 15 and 16 are first of all interengaged to hold the endmost rectangular portions in overlapping relationship. The flap portions are then folded inwardly until they are flush with the inside of the carton. The flap portions are then pressed downwardly from the interior of the carton so that the parts 13 overlap, and it will be seen that the flap portions make edge-on engagement at the points 14. The flap portions in this position will possibly project upwardly slightly into the interior of the carton and consequently 40 when the carton is filled there will be a tendency for the flap portions to straighten out, but any movement of the flap portions beyond a horizontal position will be prevented by their interengagement at the points 14. The bottom of the carton therefore will, to a certain extent, 45 have shock absorbing qualities, thus rendering the carton particularly suitable for carrying fragile articles such as, for example, glass bottles.

When the carton has been filled, the flap portions 1-5 will be folded inwardly along the crease lines 12 in their correct order.

Flaps 2 and 4 will first of all be folded inwardly, the handle portions 17 of these two flap portions being folded upwardly so that they project at right-angles to the flaps. Flap portion 5 is then folded downwardly on to flap 2, and finally flaps 1 and 3 will be folded inwardly, the 50 handle portions 17 projecting upwardly through the registering slots 20. The carton will, in this way, remain closed and can be carried comfortably in one hand, the fingers being passed through the registering slots 18.

It will be appreciated that the three handle portions 65 17 will lie closely adjacent one another and to ensure this, it will be noted that the crease line 19 of flaps 4 and 5 are set back slightly from the hypotenuse, whereas in the case of flap 2 the crease line 19 is set slightly forward. In this way the handle portions 17 will lie closely 70 side by side and provide what might be termed a composite laminated handle.

Figures 10, 11 and 12 illustrate a carton of larger size, and consequently the form of the blank will be slightly different from that of the blank previously described. The blank for the larger carton is illustrated in Figure 10 and it will be seen that the carton is rectangular cross-section as distinct from the square cross-sectional form of the carton previously described. The sides of the carton are again produced from five rectangular parts of the blank which are again indicated by reference numeral 10 in Figure 10, these parts being separated by crease lines 11.

The flaps forming the bottom of the carton are again indicated by reference numerals 1a-5a, but instead of being of identical form, they are necessarily of slightly different shape in view of the cross-sectional shape of the carton. The flaps again include projections 13 and recesses 14, together with slits 15 and 16, and when the carton is folded the edges of the flaps will interengage at the points 14 to give the bottom of the carton its necessary strength.

The flaps at the opposite ends of rectangular portions 10 are of quite different formation from those previously described, and in this connection it will be appreciated that as the carton has a greater carrying capacity it is proposed to construct the handle from four handle flaps 17 which are constructed integrally with flaps 1, 3, 4 and 5 and are provided with crease lines 19 arranged substantially as hitherto. In this case the flaps 1, 3, 4 and 5 are not of the right-angle triangle formation previously described.

The flaps 1, 3, 4 and 5 are folded downwardly along the crease lines 12 so that they overlap one another, the handle portions 17 all lying adjacent one another and forming a composite laminated carrying handle. Flap 2 is finally turned downwardly and the four handle portions will then project upwardly through the slot 20. As in this case only one flap 2 is provided, the latter is formed with an integral tongue 21 which, as is clearly shown in Figure 12, is intended to be tucked under the edge of the uppermost handle carrying flap so as to maintain flap 2 firmly in its closed position.

Either of the constructions previously described may, if desired, be modified in accordance with Figures 13 and/or 14. In Figure 13 the handle portions 17 are formed with oppositely arranged notches 22 which are engaged by the edge of the uppermost handle forming flap, with the object of preventing the flaps riding up the handle when the carton is being carried.

In the case of Figure 14, one of the handle portions is formed with an integral tongue 23 which is turned inwardly into the slots in the handle portions and provides a more comfortable grip.

In either of the constructions hereinbefore described, the carton may be lined with fibre glass or other suitable heat insulating material, with the object of maintaining the contents of the carton in either a comparatively cool condition, or conversely to prevent heat losses.

I claim:

1. A foldable rectangular box-like carton made up from a blank of sheet material having five successively aligned rectangular portions, the two end rectangular portions being substantially identical in size and in overlapping relationship in box forming assembly and jointly

providing one of the four vertical walls of the carton, each portion having a downwardly projecting flap to cooperatively form the bottom of the carton and an upwardly projecting flap to cooperatively form the top wall of the carton, each downwardly projecting flap being substantially a right angle triangle in form and provided with a lip projecting beyond the hypotenuse of the triangle adjacent the free end thereof to overlap superposed flaps in jointly forming the carton bottom, the two endmost flaps each having an open slot with said slots extending inwardly from the opposite edges thereof and cooperatively interfitting to lock said flaps in closed bottom forming position, each upwardly projecting flap being sufficiently long to contact the opposing side to strengthen the cross section of the carton, at least one of said upwardly projecting flaps being the same size as the carton cross section and having a closed slot with the remainder of said flaps having a handle forming tongue portion, said handle portions being insertable through said closed slot to project upwardly when said upwardly projecting flaps are folded to form the top wall of the container with said slotted flap retaining said handle portions in operative position.

2. A foldable rectangular box-like carton made up from a blank of sheet material having five successively aligned rectangular portions, the two end rectangular portions being substantially identical in size and in overlapping relationship in box forming assembly and jointly providing one of the four vertical walls of the carton, each portion having a downwardly projecting flap to cooperatively form the bottom of the carton and an upwardly projecting flap to cooperatively form the top wall of the carton, each downwardly projecting flap being substantially a right angle triangle in form and provided with a lip projecting beyond the hypotenuse of the triangle adjacent the free end thereof to overlap superposed flaps in jointly forming the carton bottom, the two endmost flaps each having an open slot with said slots extending inwardly from the opposite edges thereof and cooperatively interfitting to lock said flaps in closed bottom forming position, the first and third upwardly projecting flaps being square in form and provided with a diagonal slot, the second, fourth and fifth upwardly projecting flap being of right angle triangle formation and having a handle portion projecting from the hypotenuse, said handle portions passing through the slots of the square flaps and project upwardly when said upwardly projecting flaps are folded to form the top wall of the container.
